PAPER BURSTING TOY GUN

Alfred F. Langos, Chicago, Ill., assignor to Langson Manufacturing Co., Chicago, Ill., a corporation of Illinois

Application July 5, 1950, Serial No. 172,052

1 Claim. (Cl. 46—195)

1

This invention relates to a paper bursting toy. More particularly, the invention relates to a paper bursting toy of the type wherein a strip of feedable paper is automatically fed and sealed over an air pressure developing means having a member movably seated therein for building up sufficient air pressure to burst the paper.

In paper burster toys generally, and more particularly in paper bursting toys of the types set forth above, considerable trouble has been experienced in providing a positive acting paper feed for such toy, which would assure automatic feeding of the paper to be burst during each operation of the toy. Due to the fact that these toys are confined in their size and outside configuration in order to appeal to children, this trouble has been further amplified. While an otherwise satisfactory paper feed mechanism is known in the art, it has heretofore been impossible to incorporate such mechanism in certain toy configurations.

It is therefore one object of the present invention to provide a paper bursting toy having an improved paper feed mechanism.

Another object of the invention is to provide an improved automatic paper feed mechanism adaptable for use in a paper bursting toy having limited space available for such mechanism.

A further object of my invention is to provide a trigger actuated toy pistol paper burster, having a paper feed operated directly off of the pivoted trigger which adequately engages and feeds the paper on the cocking stroke, but on the return movement of the trigger is maintained out of engagement with the paper.

A feature of the invention is the provision in a paper burster toy pistol of a paper feed operating directly off of a pivoted trigger on the toy, which moves in an arcuate feeding path during the cocking stroke of the trigger, but which is guided out of the feed path and prevented from jamming or otherwise affecting the paper on the return movement of the trigger.

Another feature of the invention is the provision of a paper feed mechanism including an arcuately movable paper feed means tensioned by guide means during a portion of its feeding stroke for positively engaging and feeding paper, and maintained out of engagement by guide means on its return movement to prevent jamming or tearing the paper.

For a better understanding of the advantages of the invention, together with other objects and features thereof, reference is had to the following detailed description taken in conjunction with the accompanying drawings, wherein:

2

Fig. 1 is a sectional view of a paper bursting toy having a desired configuration, and showing the improved paper feed mechanism in a first operative position thereof;

Fig. 2 is a sectional view of the gun shown in Fig. 1, showing the improved paper feed mechanism in a second operative position thereof;

Fig. 3 is a perspective view of a paper feed pawl and connecting link therefor, the construction of which comprises a part of the present invention; and

Fig. 4 is a blown up, fragmentary view of the improved paper feed mechanism.

In practicing the invention, a paper bursting toy having feedable paper adapted to be intermittently fed to, and burst by a spring actuated paper bursting means, is provided. The paper bursting means is operatively connected to the toy actuating means which includes a trigger, for cocking and releasing the paper bursting means to cause the same to burst the paper. In order to feed paper to the paper bursting means, a paper feed mechanism is provided which includes an arcuately movable paper feed means operatively connected with the trigger for concurrent movement therewith. The arcuately movable paper feed means is tensioned by a guide means in the toy, and engages and feeds the paper during a portion of its arcuate travel, upon the trigger being cocked, but is prevented from engaging the paper on its return movement by reason of a guide means engageable by a portion of the paper feed means during the return movement.

Referring now to the drawings more particularly, Fig. 1 shows a paper bursting toy of the type disclosed in application Serial No. 114,113, filed September 6, 1949, of Otto E. Langos, inventor, and comprising a housing 11 having a gun configuration. Carried in the housing 11 is a roll of feedable paper 12 which is fed upwardly through a paper guideway 13 past a paper bursting means including a cylinder 14 slidably seating a piston 16 which is connected to a piston rod 17, and driven by a coil spring 18. Paper 12 is sealably closed over an aperture 19 in cylinder 14, by an apertured, pivoted breech member 21, and is burst by the air pressure built up in cylinder 14 during the compression or bursting stroke of piston 16.

Piston 16 and piston rod 17 are cocked against the action of coil spring 18, by an actuating means including a toggle lever assembly comprising a pair of double levers 22 and 23, a coil tension spring 24, and a key member 26 driven by a trigger 27 pivoted on housing 11 by means of

rivet 28. The actuating means detachably engages piston rod 17 to cock the same, and is disengaged therefrom at the end of the cocking stroke, to allow piston 16 to be driven rearwardly by coil spring 18 for bursting paper 12. For the purpose of feeding fresh portions of paper to aperture 19 during each cocking stroke of the toy, an improved paper feed mechanism comprising an arcuately movable paper feed means operatively connected to trigger 27, is provided.

The paper feed means includes a lever extension 29 formed on trigger 27 to which a feed pawl 31 is operatively connected. As is best seen in Fig. 4, feed pawl 31 normally engages paper 12 to press the same against paper guideway 13, and is connected by a resilient link 32 to lever extension 29 on trigger 27. Link 32 is pivotally mounted on a pin 33 which protrudes from a recessed portion 34 formed in lever extension 29. Recessed portion 34 forms a guide edge or stop 36 on extension 29 which cooperates with link 32 to force feed pawl 31 upwardly upon trigger 27 being moved rearwardly on its cocking stroke. In the idle position, feed pawl 31 is biased downwardly into cooperation with paper guideway 13, by a bias spring 37 coacting with link 32, and is prevented from dropping out of engagement with paper guideway 13, by a stop pin 38 protruding from housing 11. On the upward or feeding stroke of feed pawl 31, link 32 cooperates with a guide means 39 fixed to housing 11 in a manner, hereinafter to be described, such that feed pawl 31 is maintained in contact with paper 12 during the greater portion of its feeding stroke, and is maintained out of contact with said paper on the return movement.

Referring to Fig. 3, link 32 consists of a flat resilient strip having one end 41 curled to fit about pivot pin 33, and a downwardly extending, integral, side flange 42 formed on the remaining end 43 thereof, upon which feed pawl 31 is mounted. Substantially opposite flange 42, is a rectangular notch 44 formed in link 32, and which cooperates with guide means 39 on the feed stroke, in the following manner. Adverting again to Fig. 4, upon trigger 27 being pulled rearwardly, guide edge or stop 36 forces link 32 upwardly. Rectangular notch 44 is cut sufficiently deep, and is so positioned on link 32, that link 32 rides over guide means 39, with the side of notch 44 engaging one portion or surface 46 thereof, thereby maintaining feed pawl 31 in contact with feedable paper 12. Guide means 39 is so shaped, that guiding surface 46 tensions feed pawl 31 against the feedable paper, and then towards the end of the feeding stroke, allows the pawl to snap away from the paper to the position shown in Fig. 2. Likewise, due to the shape and position of guide means 39, on the return movement of trigger 27, end 43 of link 32 engages a second portion or guiding surface 47 of guide means 39, which action results in maintaining feed pawl 31 out of contact with paper 12 on its return movement; thereby preventing the feed pawl from pulling paper 12 downwardly and jamming or tearing the same. By reason of its simple construction and mode of operation, the improved paper feed mechanism can be easily incorporated into a paper bursting toy having any desired configuration; however, it is particularly well adapted for toys wherein the space available for a paper feed is rather limited. As is apparent from the embodiment shown, the paper feed is ideally suited for a Western type gun, due to the small

space available for an automatic paper feed in that type of gun.

In operating the gun, trigger 27 is pivoted rearwardly about pivot pin 28, causing a bifurcated, integral extension or lever arm 51 having a roller 52 supported between the arms thereof, to be pivoted forwardly. Roller 52 normally engages a cam surface 53 formed on the rearward edge of key member 26, and upon being forced forwardly, serves to drive key member 26 forwardly. Mounted on the forward end of key member 26 is toggle lever assembly 22, 23 comprising a pair of double levers each of which straddles key member 26, and is fulcrumed by a pivot pin 54. Double lever 22 also straddles piston rod 17, and is fulcrumed on housing 11 by pivot pin 55. Double lever 23 is fulcrumed on key member 26 by a pivot pin 57, and has its upper end joined together by a crosspin 58. In the idle position, crosspin 58 is biased upwardly by spring 24, and normally seats in a shoulder 59 formed in the lower edge of piston rod 17. Upon key member 26 being driven forwardly, this motion is transmitted through the toggle lever assembly 22 and 23 to piston rod 17 to cock the same.

Simultaneously with the forward movement of key member 26, pivoted breech 21 is sealably closed over aperture 19, which is formed in a rubber grommet 61 fitted over the end of cylinder 16, by means of a connecting link 62 pivotally connected to breech 21 by a pivot pin 63. Link 62 has an elongated slot 64 formed in its forward end which cooperates with a pin 66 on key member 26, to provide a lost motion connection for breech 21. Hence, breech 21 is not closed over aperture 14 until after the paper feeding operation is completed.

On the forward end of key member 26, there is a rounded shoulder or cam surface 67 which engages a stationary pin 68 in housing 11, upon the key member 26 nearing the forward limit of its travel, as is illustrated in Fig. 2. Upon shoulder 67 striking pin 68 and continuing to move forwardly, key member 26 is tilted downwardly on its line of secondary movement. It should be noted that the fulcrum pin 54 that connects double levers 22 and 23, normally bears against a round shoulder 69 formed on the lower edge of key member 26, and, as is best shown in Fig. 2, upon the key member 26 reaching the forward end of its travel, pin 54 rides off the shoulder 69 and enters a recess 71 adjoining the shoulder 69. This prevents any further pivoting of the double lever 23, which is held locked against further angular movement by the combined action of double lever 22 and key member 26 so long as the key member is in the extreme forward part of its travel. Therefore, as the key member 26 is tilted downwardly upon engaging stationary pin 68, double lever 23 is pulled downwardly to clear the crosspin 58 from shoulder 59 in piston rod 17. Piston 16 is then free to move rearwardly under the pressure of coil spring 18 on its paper bursting stroke. Meanwhile, trigger 27, key member 26, feed pawl 31, movable breech 21, and toggle levers 22 and 23, are held in the position shown in Fig. 2.

As piston 16 moves rearwardly, it builds up air pressure within cylinder 14 in back of the paper strip 12 which is clamped over aperture 19 in grommet 61 by movable breech 21. Breech 21 has a centrally disposed hole, the outline of which is shown at 73, extending therethrough in registry with the aperture in grommet 61. Therefore, upon the air pressure within cylinder 14 reach-

ing a certain value, the paper strip 12 sealing aperture 19 suddenly bursts with a loud report. Subsequently, trigger 27 is released, allowing all of the parts controlled thereby to assume their normal position shown in Fig. 1, by reason of the action of bias spring 24. In returning, crosspin 58 rides along the lower edge of piston rod 17, and eventually seats in shoulder 59. Movable breech 21 is pivoted outwardly by lost motion link 62, and feed pawl 31 is returned to its idle position in the above described manner. From the foregoing description, it is seen that the present invention provides a positive acting paper feed which is simple in construction, and which can be incorporated into a paper bursting toy having limited space available for an automatic paper feed. The invention assures that an unbroken portion of paper is fed to the paper bursting means during each operation of the gun, and prevents tearing or jamming of the paper during the return stroke. Thus, automatic paper feeding is provided, and proper operation of the gun is assured.

Obviously, other modifications and variations of the invention are possible in the light of the above teachings. It is therefore to be understood that changes may be made therein which are within the full intended scope of the invention as defined by the appended claim.

I claim:

In a paper bursting toy having feedable burstable paper and means adapted to be cocked and released for bursting said paper, the mechanical means for feeding the paper through the gun and for cocking and releasing said paper bursting means to cause the same to burst the paper, said

mechanical means including in combination a pivoted trigger adapted for operation in a cocking movement and in a return movement, a paper feed mechanism including an arcuately movable flat resilient arm pivoted at one end to said trigger, having a paper feed member secured thereon at the other end and being concurrently operable with the trigger for engaging and feeding said paper during a portion of the travel of said trigger while in a cocking movement, said resilient arm having a notch portion and a shoulder portion spaced in order respectively from the pivoted end of said arm, and fixed guide means on said toy spaced relative to the arcuate travel of the arm so that the notch of said arm straddles the fixed guide means and has an edge thereof in engagement with said guide means during a paper feeding operation, with said guide means engaging said shoulder portion of said flat resilient arm on the return movement of said trigger for pivoting said arm on said trigger and maintaining the feed member on the arm out of contact with said paper during such return movement so as to prevent tearing or displacement of the paper upon such return movement.

ALFRED F. LANGOS.
